Fig. 7

To all whom it may concern:

Be it known that I, Leo K. Stupell, a citizen of the United States, and a resident of the city of New York, county of Bronx, and State of New York, have invented a new, original, and ornamental Design for a Key, of which the following is a specification, reference being had to the accompanying drawings, forming a part thereof.

Fig. 1 is a top end view of a key, showing my new design.

Fig. 2 is a front view.

Fig. 3 is a bottom end view.

Fig. 4 is a side view.

Fig. 5 is a back view.

Fig. 6 is a cross sectional side view taken along the line 6—6 of Fig. 2.

Fig. 7 is a cross sectional view taken along line 7—7 of Fig. 2.

I claim:

The ornamental design for a key, substantially as shown.
